Patented Nov. 16, 1920.

FIG. 2

Inventor

Robert L. Welch

By *Witherspoon Co.* ^{W.H.S.}

UNITED STATES PATENT OFFICE.

ROBERT L. WELCH, OF MONTREAL, QUEBEC, CANADA.

WRAPPING-PAPER-SERVING APPARATUS.

1,358,904.

Specification of Letters Patent. Patented Nov. 16, 1920.

Application filed June 25, 1917. Serial No. 176,855.

To all whom it may concern:

Be it known that I, ROBERT L. WELCH, a subject of the King of Great Britain, and resident of the city of Montreal, in the Province of Quebec and Dominion of Canada, have invented certain new and useful Improvements in Wrapping-Paper-Serving Apparatus, of which the following is a full, clear, and exact description.

10 This invention relates to improvements in wrapping paper printing and serving apparatus, and the object of the invention is to provide an apparatus which will be dust-proof, and therefore preserve the printing device from clogging with accumulations of dust and also preserve the paper itself in sanitary condition free from dust.

20 A further object is to provide a device which will be durable in construction and handsome in appearance, and will at the same time render the withdrawing and tearing off of paper easier and more accurate than is the case with the serving rolls ordinarily used.

25 A still further object is to provide a tearing off knife which will be rigid during the tearing off operation, but will be movable to permit the operator easy access to the end of the ribbon of paper.

30 The device consists essentially of a cabinet containing a roll paper holding and printing mechanism movably mounted therein on running wheels. The front of the cabinet can be removed for the insertion of 35 fresh rolls and to permit the withdrawal of the mechanism for inspection. The front is preferably provided with one or more transparent panels through which the paper rolls and mechanism can be viewed, and also with 40 slits through which the paper emerges. A tearing-off knife is pivotally mounted adjacent each slit, and is spaced from the front of the cabinet, so that a sufficient length of paper projects from the cabinet after each 45 tearing-off operation to give the operator a good grasp of the end when pulling out the next piece of paper. This tearing-off knife is spring-pressed against stops, which hold it rigid during the tearing-off operation, but 50 permit the knife to yield and expose the projecting end of the paper.

In the drawings which illustrate the invention:—

Figure 1 is a vertical sectional view of the 55 device.

Fig. 2 is a front elevation.

Fig. 3 is a fragmentary view partly in section illustrating the spring mounting of the tearing-off knives.

Referring more particularly to the drawings, 11 designates a cabinet or case of suitable construction having the front 12 thereof formed separate and removable. A paper holding and printing device 13 is mounted in the cabinet on running wheels 14, so that it may be withdrawn from the cabinet on the removal of the front.

The front consists of a plate 15 of metal or other suitable material having transparent panels 16 therein through which the mechanism 13 may be viewed. Slots 17 are provided in the front in number and position according to the number and position of paper rolls accommodated by the cabinet. Behind each of these slots, a pair of rolls 18 are mounted on the front, the bearings of one roll being rigid, while the bearings 19 of the other roll are movable, and the roll urged by springs 20 toward the fixedly mounted roll. These rolls are preferably 25 faced with rubber or other suitable material, so as to have a good grip on the paper which passes between them to the slot 17.

On the outer side of the casing, a tearing-off knife 21 is pivotally mounted adjacent each slot, the lower edges of the knives being approximately in the same horizontal plane as the slots. These knives are mounted by means of brackets 22 secured to the front 12 and provided with pins 23, which engage 30 in lugs 24 carried by the stiff knife back 25. Each lug 24 and the portion of bracket 22 carrying the pin 23 is hollowed out to larger diameter than the pin through part of their lengths, as shown in Fig. 3, and a helical 35 spring 26 mounted in the recess, thus formed, surrounding each pin 23. One end of each spring is secured to a bracket and the opposite end to a boss, by passing the ends of the springs through apertures 27 provided in the bracket and boss. It will 40 thus be seen that the spring tends to rotate the knife around its axis of support in one direction and to resist rotation of the knife in the opposite direction. Stops 28 are 45 provided on the front 12 to limit the movement of the knife edge away from the front under influence of the springs. The front 12 may be provided with handles 29 at each side to facilitate the drawing out operation.

A lock 30 may be provided in any suitable place in order to prevent unauthorized per-

sons opening the same and tampering with the mechanism.

- The operation of the device is extremely simple, but nevertheless, of considerable importance. The paper roll holding and printing mechanism may be of any suitable type, such, as, for example that disclosed in my U. S. Patent No. 1,131,757, issued March 16th, 1915, and will require no description.
- 10 The paper strips or ribbons are led through the apparatus to the rolls 18 and slots 17 through which they pass. The rolls 18 being spring pressed are under sufficient load to prevent their easy rotation, so that once 15 a length of paper has been drawn out and torn off, the rolls will hold the end against running back into the cabinet, and will also maintain the paper in proper tension between themselves and the printing mechanism. The tearing-off knives are held at an angle calculated to produce the best tearing-off effect, and it will be understood that while the knives are shown in the drawings as in a vertical plane, they are not limited 20 to such disposition. The angle of the knives is regulated by the stops 28 against which the knives are held by their springs.
- 25 26. The stops being on the opposite side of the axis of support from the cutting edge 30 of the knives, it will be apparent that when the paper is drawn out and torn off against the knives that the knives will be held rigid with their lower edges spaced a suitable distance from the front 12, as clearly shown.
- 35 36. When it is desired to tear off the next length of paper, the operator naturally advances his hand with fingers disposed to grasp the paper between them. The uppermost finger comes in contact with the knife adjacent its 40 cutting edge and drives it back toward the casing, thus exposing a projecting portion of the paper which can be easily and conveniently grasped. As soon as the pressure against the knife is released, it is returned 45 by its springs to the proper tearing off position.
- The rigidity of the knives in tearing off is of great advantage over the existing forms of tearing-off knife, which for the most part 50 press by gravity or mechanical means directly on the roll, and therefore yield to a certain extent to the tension of the paper in tearing. The pressure of the knife is usually all that holds the roll from free rotation, and therefore when the knife yields, it fully or partially releases the roll, so that 55 the paper unwinds during tearing, with the result that the tear, in place of extending square across the strip is at an angle or 60 curve, or as occurs in many cases, the tear runs square across for a part of the distance and then makes a sudden turn, forming a projecting tongue at one edge of the paper. Furthermore, with the ordinary

tearing off means, the end of the strip is 65 completely covered by the knife, so that to get at the end in order to pull off a fresh length, it is necessary to manually rotate the roll. According to this invention, the paper is held against movement by means 70 entirely independent of the tearing-off knife and remote from the paper rolls, so that movement of the knife to follow the decrease in size of the roll is not necessary. The knife can therefore be mounted so as to be absolutely rigid during the tearing-off 75 operation, and the paper holding means can exert uniform holding effect, regardless of the size of the roll, and in amount sufficient to hold the paper against movement during 80 the tearing operation. These features result in every tear being square across the sheet for the entire width. The mounting of the tearing-off knives remote from the roll also permits the knives to retreat and expose a 85 portion of the end of the paper to the operator's grasp, thus greatly expediting the removal of paper. Such an arrangement is not possible with the tearing-off knife in contact with the roll, as is ordinarily the 90 case.

From the foregoing description, it will be apparent that in addition to providing a cabinet of attractive appearance, which protects the paper and printing mechanism 95 from dust and other foreign matter, the invention facilitates the removal of paper and provides for absolute accuracy in tearing off, thus eliminating waste.

Having thus described my invention, 100 what I claim is:—

1. In a paper holding device, a cabinet including a removable front closure plate, a paper holding rack movably mounted within the cabinet, said front plate having openings 105 for the egress of paper, and individual tearing-off knives for said openings positioned to determine the tearing-off line, some distance from the cabinet front, said knives being movable clear of the paper to expose 110 paper projecting beyond the cabinet front.

2. In a paper holding device, a plate having an opening therein for the passage of paper, a paper tearing off knife adjacent the opening, brackets pivotally supporting 115 the knife, said brackets and knife having intercommunicating recesses, and springs in said recesses each having one end fixed in a bracket and the opposite end in the knife, said springs being arranged to yieldingly 120 hold the knife in tearing-off position, whereby the knife may be moved to expose paper projecting through the plate opening, and means holding the knife rigid during tearing-off.

In witness whereof, I have hereunto set my hand.

ROBERT L. WELCH.
